UNITED STATES PATENT OFFICE.

WILLIAM M. BRUCE, JR., OF SPRINGFIELD, OHIO.

TELEGRAPHY.

1,352,873.

Specification of Letters Patent. Patented Sept. 14, 1920.

Application filed May 15, 1916. Serial No. 97,648.

To all whom it may concern.

Be it known that I, WILLIAM M. BRUCE, Jr., a citizen of the United States, residing at Springfield, in the county of Clark and State of Ohio, have invented certain new and useful Improvements in Telegraphy, of which the following is a specification.

My invention relates to improvements in telegraphy and especially in receiving mechanism, particularly adapted for use with submarine cables or high capacity or similar conductors where weak currents only can be employed and it relates more particularly to that class of receiving and translating devices in which variable resistance such as selenium is employed for operating the translating device. I have adapted my devices to systems of telegraphy where impulses of opposite polarity of current follow each other either at the end of each character or at the beginning and end of each character though parts of the system or apparatus may be employed with any of the well known systems.

My present invention has for its object the improvement of the selenium organism and a method of projecting the light thereon so as to secure a higher efficiency from the selenium cells.

Another object is to improve upon the circuits for the translating devices connected to the selenium organism with a special view to maintaining a proper zero in the translating devices.

With these primary objects and others which will appear from the description of the devices, my invention consists in the instrumentalities and circuits hereinafter described and set forth in the claims.

In the accompanying drawings:

Figure 1 is a diagrammatic view illustrating the arrangement of the selenium organism, the light projecting and deflecting means; also the local circuits for controlling the translating devices from the selenium organism.

Figs. 2, 3 and 4 are detail views more or less diagrammatic showing the arrangement of the individual units or cells composing the selenium organism and the manner of distributing the light and shade thereon.

Fig. 5 is a similar view showing a modification.

Fig. 6 is a diagrammatic view showing a somewhat modified form of circuit.

Fig. 7 is an enlarged view of a selenium

organism showing somewhat in detail the mechanical construction of same.

Like parts are represented by similar characters of reference in the several views.

As shown in Fig. 7 the selenium organism is made up of a series of units or cells and each unit or cell is composed of a series of metallic plates *a* and *a'* and *b* and *b'*, separated from each other by insulating material and with the selenium arranged in the spaces between the plates so as to secure a very thin film or surface of the selenium. Also as shown in Fig. 7 these cells or units are arranged in groups and as shown in Figs. 2, 3, 4 and 5 these groups are electrically connected preferably in multiple and I preferably arrange them in pairs so that one cell of each group is in each pair as shown in Figs. 1 to 4 inclusive, although they may be arranged as shown in Fig. 5 with the cells forming the groups spaced apart.

Instead of placing these cells close together as has been the usual method I space the cells or pair of cells apart a distance not less than the width of one cell or unit and where the cells are arranged in pairs I also separate the cells of the pairs by a slight space.

For operating the mechanism I employ a source of light *c* (see Fig. 1) in front of which there is preferably placed a lens *d* and a perforated screen *e* by means of which there is projected on the mirror *f* a series of light bands or bars separated from each other by a series of shadows or dark bands or bars. The mirror *f* in turn is arranged to project these bars into the selenium unit shown as *s* in Fig. 1 preferably through a lens *d'*; this mechanism all being so installed and adjusted that the bands or bars of light and shade will be projected on the selenium unit with the bands of light normally in the spaces between the units and the shadows on the cells or selenium units as indicated in Figs. 1, 2 and 5. The mirror *f* is arranged to be deflected by the receiving current preferably by mounting it upon an ordinary suspended coil such as used on galvanometer or siphon recorder and the deflection of the mirror is adjusted so as to alternately bring the light bars on one or the other group of cells while the remaining group remains in shadow. Where the individual cells are arranged in pairs as shown in Figs. 2, 3 and 4 this is obtained

by having one more light space than there are cells and, as these light spaces or bars normally occupy the spaces between the cells when the mirror is shifted in one direction or the other all the cells in one group will be in the light and those of the other group will be in shadow, this is illustrated in Fig. 3, where the cells at the left of each pair are shown in the light while in Fig. 4 those at the right are shown in the light. In the modification shown in Fig. 5 where the groups are separated instead of being arranged in pairs, the same result is accomplished by arranging the light bars normally on one side of the cells of one group and on the opposite side of the cells of the other group, the central light space in this case being of double width so that as the image of the light and dark streaks is shifted in one direction or the other the cell on one side of said space is exposed to the light and that on the other side remains in darkness.

As above stated I space the cells or bars of light apart a distance not less than the width of one cell with the light bars substantially equal to the width of the cell. Where the adjustments are very delicate as for instance in duplex sending, I make the space between the cells slightly greater than the width of the light bar so that minute deflections of the mirror may occur without exposing the edge or edges of the adjoining cells to the light by these variations, also by having the spaces slightly wider than the cell or the light beam the adjoining cells are kept in perfect shadow and by the deflections of the mirror are either all exposed to the light or all in the shadow, thus securing a very quick and positive response in the relay from the shifting light beams.

The electrical circuits may be described as follows:

g is the cable or conductor and g' the artificial line by which duplex sending is provided for, g^2 is the line to the sending instrument and g^3 is the receiving instrument carrying the mirror f . The coil f' of the receiving instrument g^3 is connected across the bridge between the conductor and artificial by the usual circuits 1 and 2 so as to receive the impulses coming from the conductor g and permit the transmission of sending impulses from g^2 without affecting the receiving device. One group of cells of the selenium organism is connected by wire 3 to one pole of the battery X and the other group by wire 4 to the opposite pole of the battery X . Branch connections 5 and 6 from lines 3 and 4 are provided with proper resistance r and r' forming the four arms of a bridge the diagonal of which formed by the wires 7 and 8 include the relay or translating device h . These connections are such that if the resistance of either group of selenium cells is

changed the balance of the bridge will be disturbed and an impulse of current of one polarity or the other will be sent from battery X to the relay h over the following circuit: battery X , branch 5, resistance r , wire 7, relay h , wire 8 to one side of the selenium cell and by wire 4 back to battery X or if in the opposite direction from battery X , branch 6, resistance r' , wire 7, relay h , wire 8 to the opposite side of the other group of cells.

Now, I have found in practice that unless this selenium organism is made with the most minute accuracy and the thickness of the selenium body reduced to minute proportions that the inertia of the selenium will prevent the relay h from returning sharply and quickly to zero in response to the impulses of current and to overcome this I insert in the line 8 in series with the relay a condenser i and I have found that by this means when impulses of opposite polarity are employed the impulse of current operates the relay sharply and quickly and the condenser permits it at once to return to its zero position when otherwise it would be deflected or remain in its deflected position owing to the inertia of the selenium element.

It is obvious that the smaller the mass of selenium the higher the resistance and the less current that can pass through, on the other hand the larger the mass of selenium the more inert material there is unaffected by the light and the more sluggish the action of the relay but by the use of the condenser in the circuit I have found that I can materially decrease the resistance of the cells and use a larger mass of selenium (and consequently more current) without the inertia thereof affecting the relay or its positive zero.

This is particularly advantageous where a Morse system is employed and the impulses used to operate a sounder or other simple translating instrument.

Also I have found that by the use of the condenser in connection with the selenium organism and the relay the bridge across which the relay is connected need not be accurately balanced. I have, for instance, been able to operate the relay with a difference of 7000 ohms in the arms of the bridge and found the relay maintained a perfect zero where a difference of 5 ohms without the condenser would destroy the accuracy of the operation of the relay.

I have shown in Fig. 1, the relay h operating between the contacts h' and h^2 connected to the opposite ends of a divided battery x^2 the center of which battery is connected by wire 9 to a polarized relay j the circuit of which is completed by wire 10 to the vibrating contact h^3 of the relay h . This polarized relay j may be connected to operate the usual

sounder *k* over the usual local circuit from the battery *x*³.

In Fig. 6 I have shown a modified form of circuit in which the groups of cells *a* and *b* 5 are connected to the opposite sides of the battery *x* by the wires 3 and 4 with the branches 5 and 6 leading direct to the polarized relay *j*', the circuit for which is completed by wire 8 having condenser in series to the opposite 10 sides of the cells or groups of cells *a* and *b*. This arrangement dispenses with the use of the suspended coil relay *h* and I have found this to be possible with the use of a condenser *i*' and where the selenium organism is made 15 up with sufficiently low resistance to permit an amount of current sufficient to operate a relay of this character.

Having thus described my invention, I claim:

- 20 1. A receiving device for telegraphy, comprising a selenium organism composed of a plurality of separate units or cells spaced apart a distance not less than the width of the individual units or cells, a source of light and means for deflecting the said light in bars of a width substantially equal to the width of the individual cells, said bars of light being separated by shadows equal in width to one or more of said individual 25 cells, and a deflector arranged to shift the bars of light and shadow in either direction to a distance substantially equal to one of said cells as and for the purpose specified.
2. In telegraphy, a receiving device, a 30 selenium organism and a source of light, and deflecting means at the receiving device to deflect the rays from said light source in parallel bars of light and shade, said selenium organism being made of a plurality of units or cells of a width substantially 35 equal to the bars of light and separated from each other by a space not less than the width of the light bars, said selenium cells being arranged in pairs, the different 40 units of each pair being electrically connected in multiple and arranged in a bridge so that one of the units of one pair in one arm of the bridge and the other unit of the pair in the other arm of the bridge, a 45 source of current, and a polar relay in the diagonal of the bridge as and for the purpose specified.
3. In a system of telegraphy, employing successive impulses of opposite current, a 50 selenium organism having a multiplicity of

units or cells which are arranged in two arms of a bridge, a polarized relay connected across the diagonal of said bridge, and a condenser in series with said relay.

4. In a telegraph system, a selenium organism for operating electrical devices, consisting of a plurality of units or cells spaced apart a distance not less than the width of the units, said units being divided numerically with half of the units connected in 60 multiple in one circuit and the other half connected in multiple in another circuit, a light projecting mechanism comprising means for projecting bars of light substantially equal to the width of a unit and 65 spaced apart by shadows of a width not less than two of said selenium units or cells, and means for deflecting said bars of light or shade so that all of said units shall be 70 in shadow or one half in shadow and the 75 other in light.

5. In a telegraphic system employing impulses of opposite polarity, a selenium organism comprising separate units or cells arranged in groups with the cells of each 80 group connected in multiple one of the other, a light projecting device for deflecting alternate bars of light and shadow on said cells, and means for deflecting the same to cause the light or shade to 85 cover said units, a connection from said multiple sets of units to a polarized relay, and a source of current supply therefor, and condenser in series with said relay as and 90 for the purpose specified.

6. In a telegraph system, a selenium organism of a plurality of separate cells spaced apart, a source of light, means for projecting the said light in bars of a width substantially equal to the width of the cells 95 and separated by shadows equal in width to one or more of said cells, said cells being spaced apart a distance greater than the width of the light bars, and a deflector to shift the bars of light in either direction to 100 a distance substantially equal to one of said cells, and electrical connections from said cells to a translating device as and for the purpose specified.

In testimony whereof, I have hereunto set 105 my hand this 3rd day of May, 1916.

WILLIAM M. BRUCE, Jr.

Witness: CHAS. I. WELCH.
